UNITED STATES PATENT OFFICE.

WALTER T. HATHAWAY, OF BROOKLYN, NEW YORK, ASSIGNOR TO THE FIRM OF COLGATE & COMPANY, OF NEW YORK, N. Y.

DESIGN FOR AN EXHIBITING-TRAY.

SPECIFICATION forming part of Design No. 35,375, dated December 3, 1901.

Application filed November 11, 1901. Serial No. 81,967. Term of patent 7 years.

To all whom it may concern:

Be it known that I, WALTER T. HATHAWAY, a citizen of the United States, and a resident of the city of New York, borough of Brooklyn, 5 in the county of Kings and State of New York, have invented and produced a new and original Design for an Exhibiting-Tray, of which the following is a specification, reference being had to the accompanying drawings, forming a part thereof, in which—

Figure 1 is a plan view of an exhibiting-tray, showing my design; and Fig. 2 is a sectional view thereof.

The leading feature of my design for an exhibiting-tray consists in the rectangular box-like body portion in which is arranged a partition which is transversely inclined and provided with a series of openings.

Referring particularly to the drawings, it will be seen that the major portion of the 20 walls of the openings are curved, while the upper portions of the walls are on a straight line or parallel with the adjacent side of the body.

Having thus described my invention, I 25 claim as new and desire to secure by Letters Patent—

The design for an exhibiting-tray as shown and described.

In testimony whereof I have signed my 30 name to this specification in the presence of two subscribing witnesses.

WALTER T. HATHAWAY.

Witnesses:

WM. P. WARD,
LOUIS McDAVIT.
